UNITED STATES PATENT OFFICE

JOHN S. MCPHERSON, OF COLUMBUS, OHIO, ASSIGNOR TO THE BUCKEYE STEEL CASTINGS COMPANY, OF COLUMBUS, OHIO

MEANS FOR INTERLOCKING CAR TRUCK PARTS

Application filed May 29, 1930. Serial No. 457,326.

This invention relates to improved means for interlocking the spring plank and spring seat of a railway car truck to the spring seat portion of the tension member of a side frame, and the present invention was designed primarily to eliminate the use of bolted connections. Such connections are undesirable because the bolts are liable to become loose or lost, and otherwise not make a positive means of retaining the spring seat member against horizontal displacement on the spring plank.

One of the objects of the present invention is to provide interlocking means for these parts, which are integral portions of the parts themselves, so that these elements may be cast as portions of the parts.

Another object is to provide the spring seat portion of the tension member of the side frame with an upstanding boss which will not only extend through the spring plank for interlocking that member to the side frame, but will also project into the spring seat and interlock therewith.

A further object is to furnish interlocking means of this character, which will prevent the spring seat from any horizontal displacement relatively to the tension portion of the side frame and the spring plank, and which yet allows these parts to be disassembled by relative vertical movements.

With the foregoing objects outlined and with other objects in view which will appear as the description proceeds, the invention consists in the novel features hereinafter described in detail, illustrated in the accompanying drawings, and more particularly pointed out in the appended claims.

Referring to the drawings,

Fig. 1 is an elevation of the lower portion of the tension member of a side frame, showing a part of the interlocking means.

Fig. 2 is a combined plan view of the medial portion of the side frame, the parts at the left of the line 3—3 being shown in top plan, and the parts at the right in bottom plan.

Fig. 3 is a vertical sectional view of such a side frame on the line 3—3 of Fig. 2.

Fig. 4 is a view similar to Fig. 3, but showing the side frame in assembled relation with the spring plank, spring seat, bolster and

springs, portions only of the spring plank and bolster being shown in this view, and the springs being diagrammatically illustrated.

Fig. 5 is a top plan view of the spring seat.

Fig. 6 is a side elevation of the spring seat.

Fig. 7 is a front elevation of the same.

In the drawings, 1 designates a side frame having the usual bolster opening 1a, into which an end of the bolster 2 projects. This end of the bolster rests on springs 3 which are supported by a spring seat 4 that rests upon a spring plank 4a which also projects into the bolster opening.

In accordance with the present invention, the tension member 1b of the side frame has projecting upwardly from its medial portion, an annular boss 5, to extend through an aperture 5a, positioned in the bottom of the spring plank, for the purpose of interlocking the spring plank with said tension member.

Heretofore, proposals have been made to interlock the tension member to the spring plank by similar means, but in accordance with my invention, the boss 5 is extended upwardly to an elevation above the upper surface of the bottom of the spring plank, and this projecting portion of the boss is provided with four notches 8 to interlock with depending ribs 9 and 10, arranged in the under side of the spring seat 7.

As best shown in Fig. 5, the ribs 9 and 10 are arranged in cruci-form relation, and of course, the notches 8 of the boss are positioned at 90 degrees relatively to one another to accommodate the arrangement of the ribs.

After the spring plank has been placed on the tension member of the side frame in such manner that the boss 5 projects through the opening 5a, and the spring seat 7 has been superposed on the spring plank in such manner that the ribs 9 and 10 engage the notches 8, it will be understood that the pressure of the bolster 2 on the springs 3 will cause the spring seat, spring plank and tension member of the side frame to maintain their assembled relation, and there will be no horizontal displacement of these parts relatively to each other.

Obviously, the parts may be disassembled by lifting the spring seat 7 away from the

spring plank, and the spring plank away from the tension member of the side frame.

This particular arrangement has been designed to replace "arch bar" frames on rail-
5 ways, and manifestly, this interlocking arrangement may be employed wherever it is desired to interlock the side frame, spring plank and spring seat to one another.

From the above description it is believed
10 that the construction, operation and advantages of the invention may be readily understood, and it is obvious that changes may be made in the details disclosed, without departing from the spirit of the invention, as
15 expressed in the claims.

What is claimed and described to be secured by Letters Patent is:

1. In combination, a car truck side frame member, a spring plank resting thereon, a
20 spring seat member resting on the spring plank, and means rigidly united with one of said members, projecting through the spring plank and interlocking with the other one of said members by a notch and rib con-
25 nection.

2. In combination, a car truck side frame member, a spring plank resting thereon, a spring seat member resting on the spring plank, and means rigidly united with one of
30 said members, projecting through the spring plank and interlocking with the other one of said members by a notch and rib connection, said means including an annular boss.

3. In combination, a car truck side frame member, a spring plank resting thereon, a spring seat member resting on the spring plank, and means rigidly united with one of said members, projecting through the spring plank and interlocking with the other one of
40 said members by a notch and rib connection, said means including an annular boss pro-
vided with a notched extension.

4. In combination, a car truck side frame member, a spring plank resting thereon, a
45 spring seat member resting on the spring plank, and means rigidly united with one of said members, projecting through the spring plank and interlocking with the other one of said members, said means including a boss,
50 and ribs on one of said members interlocking with said boss.

5. In combination, a car truck side frame member, a spring plank resting thereon, a spring seat member resting on the spring
55 plank, and means rigidly united with one of said members, projecting through the spring plank and interlocking with the other one of said members, said means including a boss having notches, the last mentioned member
60 having ribs projecting into said notches.

6. In combination, a car truck side frame member, a spring plank resting on said mem-
ber, a spring seat member resting on said
65 plank, interlocking means extending through
the plank and including a notched element

rigidly united with one of the members, and ribs rigidly united with the other member and engaging said notches.

7. In combination, a car truck side frame having a tension member provided with an upwardly projecting boss portion, a spring plank resting on said tension member and having an aperture through which the boss portion extends, a spring seat resting on the plank and having an interlocking portion, one of said portions being provided with ribs and the other portion being notched to receive said ribs.

8. In a car truck, a side frame tension mem-
ber provided with an upwardly extending
boss provided with notches in the top thereof,
a spring plank resting on said tension mem-
ber and having an aperture through which
the boss extends, and a spring seat resting on
the spring plank and having ribs on its under
side extending into said notches.

9. A car truck including a side frame ten-
sion member provided with an upwardly ex-
tending annular boss having notches in the
top thereof, a spring plank resting on said
tension member and having an aperture
through which the boss projects, and a spring
seat resting on said plank and provided on
its under side with cruci-form arranged ribs
which project into said notches.

10. A car truck side frame having a tension member provided with an upwardly extend-
ing substantially circular boss having sub-
stantially radial notches in its upper edge,
and a spring plank and superposed spring
seat resting on said tension member and inter-
locked with the boss, the spring seat having
portions extending into the notches for also
interlocking the spring seat with the boss.

11. A car truck side frame having a ten-
sion member provided with an upwardly ex-
tending boss having notches in its top, and a
spring plank and superposed spring seat rest-
ing on said tension member and interlocked
with the boss, the spring seat having portions
extending into the notches for also interlock-
ing the spring seat with the boss.

In testimony whereof, I have signed this
specification.
